UNITED STATES PATENT OFFICE.

BENJAMIN M. LEWIS, OF EDINBURG, TEXAS.

REFLECTOR.

Application filed January 26, 1927. Serial No. 163,743.

This invention relates to new and useful improvements in reflectors and has for its primary object to provide a slowly rotating multi-mirrored reflector especially useful in 5 show windows of business houses for displaying signs or other articles of merchandise or for reflecting multi-colored light rays so as to attract the attention of passers-by to articles within the window.

10 In carrying out my invention I provide a rotating reflector unit within which may be disposed a source of illumination covered by a multi-colored lens shield, or in lieu thereof an article tray for providing in the first instance a highly novel and beautiful light display, or in the second instance the multi-reflection of the articles upon the tray. In the first instance, a suitable sign plate may be inserted in front of the reflector for attractively advertising the wares of a particular establishment.

15 A further and important object is to provide a reflector of this character wherein a single power means is employed for the rotation of the reflector per se, and the rotation of the multi-colored lens shield for the light source, or for the article supporting tray when the same is employed in lieu thereof.

20 Yet another object is to provide a device of this character that may be supported at predetermined angles so as to permit of the clear view of the same regardless of the construction of the show window or other place 25 wherein the device is disposed.

25 With the foregoing and other objects in view as the nature of the invention will be better understood, the same comprises the novel form, combination and arrangement 30 of parts hereinafter more fully described, shown in the accompanying drawings and 35 claimed.

40 In the drawings wherein like reference characters indicate corresponding parts 45 throughout the several views:

Figure 1 is a rear elevation of the device.

Figure 2 is a detail vertical section thereof.

45 Figure 3 is a view partly in section and partly in top plan of an electric current distributor that is employed in association with the device for permitting the current to flow continuously to an electric lamp or to cause the rapid making and breaking of the circuit to the lamp as desired.

50 Figure 4 is a perspective of a supporting unit for a multi-lensed lamp shield or article

supporting tray, either of which may be employed in conjunction with the invention.

Figure 5 is a perspective of a bell crank shaped contact arm that forms an essential 60 element of the distributor disclosed in Figure 3.

Figure 6 is a fragmentary front elevation of the device being employed in this instance however to reflect articles of jewelry or the like that may be supported upon the tray heretofore mentioned, and Figure 7 is a detailed fragmentary section somewhat similar to Figure 2 disclosing an ornamental lamp box in position over the multi-lens 70 lamp shield.

Now having particular reference to the drawings, the present device consists of a circular pan-shaped base 5, the top wall of which is formed with a circular opening 75 within which is disposed a circular supporting plate 6 for the reflector and its associated elements. This plate 6 is pivoted at its front edge as at 7 within the base 5 in order that the same may be swung downwardly at its 80 rear end for supporting the reflector in predetermined inclined position.

Suitable locking means designated generally by the reference character 8 is employed 85 between the plate 6 and the skirt of the base 5 for maintaining the plate in predetermined inclined position.

Suitably supported upon the plate 5 adjacent the front edge thereof is a cylindrical housing 9 open at its front and rear sides, 90 said front side being formed with an inwardly extending circumferential flange 10, while directly in back of this flange and in a slight spaced relation therewith are brackets 11. The upper half of the cylinder 9 95 is slotted as at 12 so as to permit the positioning of a circular glass plate 13 within the housing between the flange 10 and brackets 11. Furthermore, the interior of the housing 9 is provided with other brackets 100 14—14 in spaced relation with the first mentioned brackets 11 so as to rigidly support a circular sign plate 15 between the brackets 11 and 14 and this in slight spaced relation with the glass plate 13.

105 The sign 15 is preferably of sheet metal having advertising indicia or the like cut therein so that the light rays within the housing may pass therethrough so that the advertising matter will be visible.

110 Arranged vertically upon the plate 5 at the rear edge thereof is a vertical stand

ard 16 through the upper end of which is journaled a horizontal shaft 17, the forward end of which projects into the housing 9, while the rear end thereof extends in back of said standard as clearly disclosed in Figure 2. Keyed to this shaft 17 in front of the standard 16 is a relatively large parabolical reflector 18 that preferably consists of a sheet metal shell having arranged upon the inner face thereof strip-like reflector mirrors 19, the shell being of such a formation and the mirrors being in the form of two sets as to provide a pair of different angled surfaces at the inner and outer ends of the reflector as in Figures 2 and 6.

Mounted upon the back side of the standard 16 beneath the shaft 17 is an electric motor 20, the armature shaft of which is equipped at one end with a worm 21 for mesh with a worm gear 22 upon the outer end of a stub shaft 23 suitably journaled in the standard 16. The inner end of this stub shaft 23 is equipped with a small spur gear 24 that has mesh with a relatively large gear 25 keyed to the shaft 17 in back of the reflector 18. Obviously the operation of the motor will occasion the slow turning of the reflector for producing effects hereinafter more fully described.

Arranged within an opening in the top side of the cylindrical housing 9 directly in front of the reflector 18 is a lamp switch unit 26 from which depends a lamp cord 27 that carries at its end an electric bulb 28.

Arranged vertically upon the supporting plate 6 of the reflector base in vertical alignment with the lamp 28 and cord 27 is a tubular shaft housing 29. Within this housing 29 is a vertical shaft 30, the lower end of which projects through an opening in the plate 6 and is equipped with a cord pulley 31. Adapted for removable disposition upon the upper end of the housing 29 and for operative connection with the upper end of the shaft 30 is a generally barrel shaped lamp shield 32, Figure 2 or an article supporting tray 33, see Figure 6. When the tray 33 is employed, it is preferable that the lamp 28 and its associated cord 27 and switch socket 26 be removed. However, the barrel shaped shield 32 is of such construction as to permit of the disposition of the lamp 28 therein as clearly disclosed in Figure 2. This shield is provided with a plurality of bull eye lenses 34 preferably of various colors.

Rigidly arranged upon the shaft 17 between the reflector 18 and gear 25 is a large cord pulley 35 over which is trained an endless cord 36 that extends downwardly and is passed through openings in the plate 6 and thence over pulleys 37-37. The runs of the cord are thence directed forwardly as in Figure 2 and trained over the pulley 31 of the shaft 30. Thus the rotation of the shaft

19 not only causes the turning of the reflector 18, but also the vertical shaft 30 and consequently the lamp shield 32 or the article supporting tray 33 as the case may be.

Also removably associated with the upper end of the shaft housing 29 beneath the shield 32 or tray 33 is an L-shaped bracket 38, the outer end of the horizontal arm of which is detachably secured to the shaft housing 29, while the outer end of the vertical arm is supported by the inner end of the horizontal motor operated shaft 17. In slight inward spaced relation with the vertical arm of this bracket is a vertical pin 39 over which is disposed a vertical sleeve 40 associated with an ornamental lamp box 41 that may be arranged over the multi-lens shield 32 for displaying interesting characters cut or otherwise formed therein as disclosed. This lamp box is employed when the sign plate 15 has been removed so that the characters will be readily observed both direct and indirect as is obvious.

The rear end of the horizontal shaft 17 is equipped with a metallic rotor 42 provided at its inner edge and at its periphery with spaced fiber inserts 43. Pivoted to a lateral support 44 formed at the side of the standard 16 is a bell crank contact 45, the unpivoted arm of which has wiping contact with the rotor 42. Mounted upon the supporting plate 6 in back of the standard 16 is an electric lamp 28, the motor 20, the rotor 42, the switch 44 and bell crank 45 are electrically interconnected and electrically connected with a source of electrical energy in such a manner that when the switch 44 is turned on the motor 20 will operate. Obviously the circuit is made to the lamp 28 by reason of the engagement of the contact 45 with the rotor 42. When the contact 45 is in the position disclosed in Figure 3 there will be a continuous circuit to the lamp 28. However, when this contact is swung inwardly in the direction of the arrow in Figure 3 so as to engage the surface of the rotor at its inner edge, the circuit will be rapidly made and broken to the lamp 28 by reason of the fiber inserts 43. The detailed construction and operation as well as the various uses of the device will be at once apparent to those skilled in the art, especially after referring to the drawings, and the present specification. Although I have herein shown and described the invention as consisting of certain detail structural elements, it is nevertheless to be understood that minor changes may be made therein without affecting the spirit and scope of the appended claims.

Having thus described the invention, what I claim as new is:—

1. A device of the class described comprising a base having an opening, a platform hingedly mounted in the opening, means for holding the platform in different tilted po-

sitions, a supporting structure rising from the platform, a reflector, means for rotatably mounting the reflector on the supporting structure, a standard rising from the platform, a multi-lens shield rotatably mounted on the standard in front of the center of the reflector, a stationary electric bulb in the shield, and means for simultaneously rotating the reflector about its axis 10 and the shield about the electric bulb.

2. In a device of the character described, a cylindrical housing, a shaft coincident with the axis of the housing, means for supporting the shaft, a reflector mounted for 15 rotation about the shaft within the housing, a stationary electric lamp arranged within the housing at the center of the reflector, a rotating multi-lens shield disposed around said lamp, a standard for rotatably mount-

ing the multi-lens shield, said standard being 20 disposed radially of the housing and perpendicularly of the shaft, an L-shaped bracket having one extremity engaged with the standard so that the arm thereof is disposed perpendicular to the standard and extends into the reflector, the other arm being disposed perpendicularly to the shaft and having its end engaged thereon, a pin disposed perpendicularly on the first-mentioned arm of the L-shaped bracket, an ornamental 30 lamp box having a sleeve disposed over the pin so that the lamp box will surround the multi-lens shield, and means for facilitating the simultaneous rotation of the reflector and shield. 35

In testimony whereof I affix my signature.

BENJAMIN M. LEWIS.
